UNITED STATES PATENT OFFICE

RODOLPHE PICKER, OF BUDAPEST, HUNGARY

CENTRIFUGE TUBE AND SPOON THEREFOR

Application filed February 20, 1929, Serial No. 341,315, and in Germany February 25, 1928.

The invention relates to an apparatus of technical and scientific precision constituted by a special spoon collecting sediments precipitated by centrifugation from liquids irrespective of their nature and by an improved centrifuge-tube corresponding to the spoon invented and constructed especially for quantitative bacteriological investigation of urine, blood and other secretions and liquids of the body taken therefrom and put in the sterile apparatus by means of an aseptic operation and containing cells, bacteria and other particles suspended in.

The practical purpose of the invention is to enable that the following can be effected in an exact, rapid and completely sterile manner and without having to employ an assistant for the purpose, viz.:

1. The preparation for and the operation of centrifugation itself,
2. The removal of the sediment from the tube for the purpose of bacteriological examination whatever kind,
3. As the chief purpose—to transfer the sediments to the surface of solid culture soils for bacteria, even if the quantity of such sediments is very small and irrespective of their nature e. g. whether of purulent or of mucous kind.
- 30 These three points at the same time also define the scientific object of the invention which is to enable the investigator to make out exactly the total amount of sediment or bacteria contained in equal portions of the original material, both in single and in set-researches.

These objects are achieved by applying according the rules of asepsis and bacteriology the apparatus, the two constituent parts of which:

- I. The improved centrifuge tube,
  - II. The spoon corresponding to it,
- represent the following shape, possess the following peculiarities and allow, each part for itself, to perform same and both together all operations particularized above and thus yield an apparatus of technical and scientific precision embodied by the drawing, its application being described hereinafter.

- 50 I. The improved tube is made of glass and

shows the length and shape of the average tubes used in centrifugating liquids, its upper half being fashioned to the form of a cylinder, its lower half to the form of a conus. But it differs from the average type by the following peculiarities, allowing the following operations:

1. The brim of the improved tube has no border nor outward bend present in the average type, but is even end of the cylinder and is

2. Fitted with two short glass rods of adequate shape, starting at right angle from the brim and standing in diametrical opposition forming two ears or lugs, lacking in the average type.

3. The bottom of the conical part of the improved tube is wider than in the average type and is

4. Fashioned to the form of a regular hemisphere, lacking in the average type.

These constructive peculiarities of the improved tube allow:

a. The inside of the tube to be cleaned perfectly by mechanical procedures, often difficult to be done exactly in the average type.

b. The tube to be grasped by means of its lugs, to be put in the casing of the centrifuge and removed therefrom, without touching its brim with the fingers,

c. To avoid all pollution of the tube and its contents from outward in performing the operations a, b, and exclude erroneous results of cultivation, very difficult to do so and impossible at all in using the average tubes and the average technic and instruments of bacteriologic work.

d. To apply a spoon corresponding to the tube and use it for all operations to be done with, partly in connection with the tube and partly with the spoon for itself, impossible to be done without it, the spoon representing the following shape, possessing the following peculiarities and allowing the following:

II. The spoon is stamped out of one piece of metal, it shows the form of a ladle, its cup being semi-globular with a corresponding excavation and an even circular brim, its long handle being flat, starting from the brim of the cup standing nearly at right angle to its horizontal diameter, and ending in a hook,

possessing the following peculiarities, allowing the following:

1. The total length of the spoon, measured from the tip of the cup to the top of the handle, is overpassing the length of the tube in which the spoon is to be applied, average 2-3 mm.

2. The cup is fashioned to the form of a regular, hollow-semiglobe, the diameter and profile of its surface being absolutely equal to the diameter and profile of the hemispheric bottom of the improved tube, in which it is to be applied.

3. The handle is a flat, elastic stick, its middle section is easily curved inwards, its terminal section at halfway bends outward to form a narrow hemicircle, then runs backwards close to the ascending leg and ends with a short arc curved outward, thus forming a long elastic hook, acting as a clip.

These constructive peculiarities of the spoon allow:

a. A spoon of required capacity to be placed in a corresponding tube,

b. The spoon to make the cup close fit—without a gap—to the bottom of the tube and to collect in its excavation all sediment precipitated by centrifugation from the liquid.

c. The spoon to be fixed during the centrifugation, without interfering with the action of centrifugal force and during the subsequent decantation of the overstanding liquid,

d. The spoon to be lifted with the sediment in its cup without a jerk from the centrifuge-tube, grasping it by its hook,

e. The spoon to be introduced in the test tube, containing the solid culture soil without loss of time and to be fixed by means of the hook to its brim in the position wanted for transferring the whole content of the cup to the surface of the culture soil wanted for the special purpose and that

f. The spoon to be removed from the test tube without the content of the tube or cup having had contact with the external world, impossible to be done in using the average tube, technic and instruments for centrifugation and bacteriological work following the centrifugation.

The drawing illustrates by way of example an embodiment of the invention and its application.

Figs. 1 and 2 are two longitudinal sectional views—being taken at right angles to each other—of the centrifuging tube fitted with a spoon, the top part of the tube being shown in view.

Fig. 3 is a view from above of the same.

The lugs or ears —2— of tube —1— are formed by glass rods united by melting to the edge of the tube. The semiglobular shaped cup —3— of the spoon, has a cubic capacity of 0.1-0.2 centimetre cube. According to experience this is sufficient to collect

the total amount of mucous sediment usually obtainable front 10 centimetre cube of clear urine. In accordance with this size of the spooncup —3—, the tip of the tube —1—, is a semi-globe of larger diameter as usual in centrifuge-tubes, in order to allow cup —3— to fit without any gap to the bottom of the tube. The handle —4— of the spoon fits the wall of the tube at both ends, but in its middle part, notably at the point where the cylindrical part passes into the conical part, it bends inwards, in order to permit the spoon to follow the action of centrifugal force. With the same end in view, when cup —3— fits to the bottom, the top end of handle —4— reaches beyond the edge of the tube, to the extent of a certain straight length, before bending to form hook —5—. The end of hook —5— is bent outwards to a short arc, to facilitate its being hung-in. The hook holds the spoon secure, in the manner of a clip, against any motion along the circumference of tube 1, but it presents no obstacle against the longitudinal motion of the handle under the action of centrifugal force, and fixes the spoon containing the sediment, when after centrifugation the overstanding liquid is decanted.

After centrifugation, the tube can be lifted easily from the casing of the apparatus, holding it by its lugs or ears 2, and after the liquid has been decanted, the sediment, which has accumulated in the cavity of the spoon, can be transferred by aid of the spoon, easily, quickly, in a sterile manner and completely (i. e. without any residue whatever) for the purpose of investigation, or further treatment. In case of transference to a solid culture soil for bacteria (agar slant) it is possible to fix the spoon by its hook —5—, to the edge of the test tube and the contents of the spoon can be transferred, without any residue, and observing the rules of bacteriological research in the most exact manner, to the slant by means of a platinum loop and after the removal of the spoon, it can be spread out on the surface of the culture soil in a thin layer.

If a mark is provided on the tube, corresponding to a cubic volume of, say —5— or —10— centimetres cube, before centrifugation all kind of calibration is avoided, thus yielding considerable saving of time.

If we use a tube on which further divisions, representing cubic centimetres, are also marked, and the lowest division of which is furthermore divided into ten parts, it becomes possible further to effect a reading of the absolute quantities of the sediment, and it becomes possible, on the basis of the quantity of bacteria bred from 0.1 cm^3 of sediment, to determine with full exactity the absolute amount of bacteria contained in the test sample and in the material forming the object of the investigation.

What I claim is:

1. An apparatus for collecting sediments therein by centrifugation, comprising a centrifuge tube and a spoon, said spoon including a cup adapted to conform to the bottom of said tube and a handle, the handle having resilient means on its outer end engaging the edge of the tube to automatically hold the cup by spring action down in fluid-tight conformity with the bottom of the tube, whereby the sediment is prevented from settling in the tube outside the cup.

2. An apparatus for collecting sediments therein by centrifugation, comprising a centrifuge tube and a spoon, said spoon including a cup and a handle, the handle being continued parallel to the side of said tube at the top for a predetermined distance and then looped downwardly, the end of said handle being formed into a spring-clip engaging the outside of said tube, whereby the component of the centrifugal force acting downwardly on said spoon is accommodated by said looped extension without placing strain on the upper edge of said tube.

3. An apparatus for collecting sediments therein by centrifugation, comprising a centrifuge tube and a spoon, said spoon including a cup and a handle, said handle having a portion sprung against the lower portion of the tube and against the upper portion of the tube, the intermediate portion of said handle being bowed inwardly to such an extent as to cause the bow to absorb the centrifugal force and straighten out to permit the spoon to follow the action of the centrifugal force.

In testimony whereof I affix my signature.
RODOLPHE PICKER.
